UNITED STATES PATENT OFFICE

166,880

COMBINED KNIFE AND SAW

Peter P. Ruppe, Grosse Pointe Woods, Mich.

Application April 24, 1950, Serial No. 9,451

Term of patent 7 years

(Cl. D22—3)

To all whom it may concern:

Be it known that I, Peter P. Ruppe, a citizen of the United States, residing at Grosse Pointe Woods, in the county of Wayne and State of Michigan, have invented a new, original, and ornamental Design for a Combined Knife and Saw, of which the following is a specification, reference being had to the accompanying drawing, forming part thereof.

Fig. 1 is an edge view of a combined knife and saw, showing my new design;

Fig. 2 is a side view thereof; and

Fig. 3 is an end view thereof.

The side not shown has substantially the same appearance as the side shown in Fig. 2.

I claim:

The ornamental design for a combined knife and saw, as shown and described.

PETER P. RUPPE.
